United States Patent Office.

JOHN F. MALLINCKRODT, OF ST. LOUIS, MISSOURI.

Letters Patent No. 92,625, dated July 13, 1869.

BRICK-MACHINE.

The Schedule referred to in these Letters Patent and making part of the same.

To all whom it may concern :

Be it known that I, JOHN F. MALLINCKRODT, of St. Louis, in the county of St. Louis, and State of Missouri, have made certain new and useful Improvements in Brick-Machines; and I do hereby declare that the following is a full and clear description thereof, reference being had to the accompanying drawings, and to the letters of reference marked thereon.

This invention relates to machines for moulding bricks and similar building-materials; and

The nature of said invention is, first, in the arrangement and operation of the devices to cause the clay to be fed out intermittently between rollers and proper guides; secondly, in the construction and arrangement of the cutter and conveyer-device operating to cut off the clay and throw the same into the moulds.

To enable those herein skilled to make and use my said invention, I will now more fully describe the detail construction and operation of my said improved machine as it will usually be applied to form bricks, such as are ordinarily applied for building-purposes, referring herein to the accompanying

Figure 1 as a sectional elevation; to

Figure 2, as a side elevation; to

Figure 3, as a top plan.

I support the operating-devices of my said machine upon a suitable frame, A, constructed of wood or cast-iron.

The power-shaft B is supported in said frame, and connects with an exterior power-source in any manner usual.

Said shaft carries the driving-pinion b, operating the spur-wheel C, the shape whereof is also held in the frame A.

From said wheel C, motion is transmitted to the feed-rollers D, which are placed on the top of the frame A, rotating on journals d resting in proper bearings d'.

Directly over said rollers D, I place the feed-hopper E, into which clay (or similar material) previously tempered is put, and from which the clay passes down between the rollers D.

On each end of the hopper E, I arrange sand-boxes F, which permit sand to reach the surface of the rollers D, and thus properly prepare them for contact with the clay.

The rollers D have collar-ridges, d'', so as to form two or more bars of clay; and the distance between the contiguous ridges is arranged somewhat smaller than the length of mould, while the rollers D are gauged to such a distance or clearance that the thickness of the clay bar will be somewhat greater than the height of the mould.

The clay, as it leaves the rollers D, passes down between the guides G, and when a sufficient quantity thereof has been forced into proper position, the flier H cuts off the required quantity and carries it radially down and throws it into the mould I, which is prepared to receive it.

In order that the rollers D may deliver the clay in such quantity, and at such times, below the guides G, as it is required for action of the flier H, I operate the rollers D by studs or pins, d'', on the ends of one of said rollers, these being carried forward by the carrier-tappets c' on the gear-wheel C. Then the rollers D are connected, by spur-wheels d', to communicate the motion from one to the other.

The flier H is secured to the shaft h, which rests on bearings in the frame A.

As has before been stated, said flier cuts off the requisite volume of clay, and has for this purpose the head-board h¹, which carries the ribs h². Said head-board is of proper size to cut off bars of clay somewhat less in width than the mould, and in order to insure the retention of the clay on said head-board, one or more of said ribs, h², are secured thereon.

To give the flier the movement required, I arrange on the disk of the gear-wheel C, the cam-groove (usually heart-shaped) c'. This actuates the roller or pin k of the slotted rod K, the same being guided by its slot k' on the shaft c.

Said rod K is thus raised and lowered, and, by the rack k' thereon, turns the pinion h³ on the flier-shaft h, thus moving the flier.

It is preferable to give the flier H an accelerated motion after it has cut the clay from the bar thereof under the guides G, so as to throw the clay with greater momentum into the mould I.

This I accomplish by the heart-shaped slot or groove c', the curvature thereof being varied in departure from the centre of the shaft c in accordance with the velocity required.

The moulds I are of the usual form, as in hand brick-making, and they are placed on the tables I' in proper position to receive the clay as it is thrown from the flier-board; and as the clay volumes upon the board h¹ are of slightly less length and slightly less width than the mould, the clay will thus be readily entered therein, and owing to the force of the projection, the clay will be spread out and properly fill the mould, as required. At the same time, owing to the greater height of the clay volume than the height of the mould, the indentations caused by the ribs h² of the flier-board will not effect the proper shape of the body of clay as filling the mould.

In order that the mould may be moved off from the position occupied in filling same on the table I', and that the superfluous clay may be cut off, I arrange the vibrating levers L on a shaft, l. Said levers have the connecting-lever l', which, at its end, has the inclined face l''. In order to throw the levers L forward by turning the shaft l, the pins d'' on the rollers D, in the rotation hereof, act against the inclined face l'' of the lever l', thus accomplishing the forward motion required.

The return motion of the levers aforesaid is induced by a weight, l'', on the shaft l, or by a proper spring.

As the mould is thus moved forward, it passes under the stretched wire M, by which the superfluous clay is severed, and the mould then reaches the inclined step N, and lands thereon, as indicated by red lines in the fig. 1, the superfluous clay being thrown off (in the latter movement to the step N) into a proper receiver.

The platform N may be hinged to the table I, so that it may be raised up, and the room occupied be economized during non-use of the said parts.

It will be more convenient to use a mould without a bottom. The same will be constructed with proper handles at the sides, so as to be carried with its narrow side downward to support the clay therein. Otherwise, the construction of the mould is in the usual manner. By the operation of the flier to throw the clay therein, the clay spreads first at its lower or impact surface, and as it gradually fills the mould, the air is permitted to escape, the process here used being, in this, closely analogous to the hand processes in common use.

Having thus fully described my said invention, What I claim, is—

1. The pinion b, spur-wheel C, provided with cam-groove c² and tappet c¹, the rollers D, guide G, and hopper E, when provided with a sand-box, F, at each side, and all constructed, arranged, and operating substantially as and for the purposes set forth.

2. The flier H, with its head-board h¹ and ribs h², vibrating on the shaft h, and operating to throw the clay into the mould, substantially as set forth.

3. The cam-groove c², pin k, rod K, rack k', when combined with the pinion h³ and flier-shaft h, substantially as set forth.

In witness whereof, I have hereunto set my hand, in the presence of—

JOHN F. MALLINCKRODT.
